UNITED STATES PATENT OFFICE.

CHARLES LANE GOODRUM, OF ROCHESTER, NEW YORK, ASSIGNEE, BY MESNE ASSIGNMENTS, TO WESTERN ELECTRIC COMPANY, OF CHICAGO, ILLINOIS, AND NEW YORK, N. Y., A CORPORATION OF ILLINOIS.

TELEPHONE SYSTEM AND APPARATUS.

1,135,011.

Specification of Letters Patent.

Patented Apr. 13, 1915.

Application filed April 1, 1905. Serial No. 253,227.

To all whom it may concern:

Be it known that I, CHARLES LANE GOODRUM, a citizen of the United States, residing at Rochester, in the county of Monroe and State of New York, have invented certain new and useful Improvements in Telephone Systems and Apparatus, of which the following is a specification, reference being had therein to the accompanying drawing.

10 My invention relates to telephone systems, and particularly to automatic exchange systems.

It has for its object the provision of improved circuits and apparatus for such systems, the simplification of both the switches and the circuits, the use of common battery, the use of party-lines, and in general improvement in all the various features which have heretofore been used in automatic systems.

15 The leading characteristic feature of my invention consists in the provision of a number of connecting switches or other means less than the total number of lines to be served thereby, for purposes of selection; and the provision of a switching means identified with each line whereby the same may become identified and connected in calling with suitable selecting and connecting apparatus. This latter is divided into groups, by means of which successive selections are made; and another feature of my invention is that these groups do not bear a decimal relation to each other of necessity, 20 but may be and are preferably arranged in what may be called semi-decimal relation, five as a multiple being substituted for 10. In an exchange of a thousand subscribers I employ what I designate as "B," "C" and "G" switches for selecting; and "A" switches for putting the lines in connection with idle apparatus of the connecting groups. Such an arrangement is typical, and will be disclosed in detail in the specification herein- 25 after. The only change required for increasing the size of the exchange to be served is the insertion and connection of more switches in their due order in the scheme. These switches would be precisely the same as the "C" switches, but would be called "D" (for 10,000 subscribers) "E" (for 100,000), etc.

An important feature of my invention is the type of switch I have evolved having,

its arms move each in a constant plane, being fed forwardly by what are called "group steps," and preferably backward by individual steps to select the proper unit in a group. The switches are mounted entire on a flat base for each one, the bank contacts being made removable without complication, so that all the operative parts of each switch are removable for inspection and repairs. By my arrangement I also economize space and protect the switches from dust; for each switch base with the parts carried on it is treated like a drawer unit in a cabinet, all cable and wiring being disposed on the back of the cabinet (or rack) and all the working parts being removable from the front.

Referring to the drawings, Figure 1 is a top plan view of a B switch. Figs. 2, 3, 4 and 5 are details thereof. Fig. 6 is a top plan view of an A switch. Fig. 7 is a vertical section thereof looking from the left. Fig. 8 is a detail of the contact banks of the A switch. Fig. 9 is a top plan view of the G switch, and Fig. 10 is a detail view of its banks. Figs. 11, 12, 13 and 14 are continuing diagrams showing respectively the circuits of the A, B, C and G switches. Fig. 15 shows a called subscriber's line circuit and his A switch when idle.

The mechanical structure of the C switch is substantially the same as that of the B switch, so I have not complicated the presentation of the case by introducing a C switch drawing, which would be almost a precise duplicate of Fig. 1.

I will first briefly outline the functions performed by the successive switching operations, so as to enable an intelligent grasp to be taken of the apparatus and circuits as subsequently described. I will then pass to some description of the mechanical structures; and thereafter will advert to some peculiarities of the circuits. Finally I will give a statement of operation which will convey the clearest idea of my system as a whole, and will point out the novelty thereof in my claims.

According to the present scheme, I provide each subscriber's line with what I call an A switch, the sole function of this switch being to connect the line when calling with an idle trunk of a first selector or B switch. The A switch is shown in Fig. 6, and it will be observed that in its bank there are

twelve contacts per row. That is to say there are twelve trunks, or twelve B switches which each line may reach, and I find that the percentage of B switches required in 5 a city exchange is commonly five per cent., rarely exceeds ten per cent., and almost never exceeds twelve per cent.

When a subscriber calls his A switch starts and instantly connects him with an 10 idle B switch. The B switch, and if the exchange exceed one thousand in size the C switch, are controlled by impulses over the vertical side of line to select a group of trunks to subsequent switches, and then to 15 select an idle trunk in the group. This brings the circuit to the G switch, which is then in its turn controlled to select the wanted subscriber's line, the same being performed by merely stepping the arm 20 around over a single set of contacts. When the wanted line is selected the condition of the switch relays is such as to leave the ringing generator on the line for a short period, then off for an interval, then on 25 again, and so forth until the called subscriber answers or the calling subscriber abandons the call and hangs up. Upon so hanging up the switches are all restored by 30 restoring magnets working back one upon another through the trunks; whereas if the called subscriber answers his line takes current, his A switch is cut off, the ringing relay is cut off, bridging battery is cut back to the calling subscriber giving talking current for his transmitter, which he did not 35 have before. In the present case, instead of employing the double motion switches commonly known as the Strowger switches the same having been improved by Messrs. 40 Lundquist, Ericsson and others, I have adopted a very different design. In the first place, my switches are all mounted upon flat bases, so they can be mounted like drawers in a cabinet; and in the second place I 45 make them separable, one part carrying the contact banks and multiple wiring connections, and the other part carrying the relays and the working magnets together with the switch arms or wipers. These second 50 parts are provided with contact terminals which when the parts are in position register with corresponding terminals on the first parts, completing the connections of the relays, etc. These second parts are removable and all of the same kind, are interchangeable, and as it is with these parts that a very large percentage of the troubles occur, it is obvious that I have achieved an important end by this arrangement; for in 55 case of any trouble with the working parts of a switch of any letter, it is only necessary to slide out the defective switch body and slide in another in its place.

60 I have chosen to depart from the decimal system of trunking because thereby I can

simplify the switches and get better results. In the ordinary Strowger switch it is customary at each completion of a link or trunk to step up the switch arm to the row of contacts desired, and then connect a so-called rotary relay which would carry the wiper around continuously until it rests upon an idle contact. In the present case I provide fifty contacts in the switch (I refer particularly to the B and C switches) 70 divided into groups of five. Each group of five small contacts is equal in angular dimension and is overlaid by a single broad contact. Each switch has a double ratchet motion; a pawl working into a coarse 80 ratchet first steps the wipers around to the group contact desired, clearing five of the small contacts at a jump; then a scape pawl working into a finer ratchet (five to one of the other) steps back the wipers one step 85 as at a time in the group thus selected until the desired unit contact is reached. Thus in these switches I only give five trunks to a switch, and I can multiply the number of switches if required. 90

In addition to the above features of novelty I provide in connection with the present system a registering scheme which enables the time of calls to be recorded. Many features of novelty will appear from the 95 description and statement of operation.

Referring now to Fig. 1 E is a base plate of metal rectangular in shape and divided along the line e' at its upper end, leaving an upper rim e to form a base for the contact banks F. Upon this base a row of socket contacts H are mounted in insulation, with which coöperate the contact terminals h mounted in a strip on the base E. These terminals h are used to complete the 105 circuits from the cable in the racks to the magnets shown on the base E.

The contact banks F are formed as an arc of a circle somewhat less than 180° , and concentric with the center or axis b of the 110 switch spindle. In the banks are the broad contacts 48, and the individual trunk contacts m^o, which will be pointed out hereafter in referring to the diagrams.

Extending across the upper end of the 115 plate E is a bridge e^o drilled at its middle point to receive the coned end of the switch spindle b. Directly in line with the opening in the bridge a similar opening is formed in the plate for the other end of the spindle. In a box secured around the foot end of this spindle is the coiled spring b^o which serves to return the spindle to initial position when released as hereinafter described. Upon the spindle are mounted the ratchet wheels b^o and b^o, the stop ratchet wheel b⁵⁰, and the wipers b', b^o, b²⁰⁰, b^o, b³⁰⁰. These may be and 120 preferably are insulated, particularly the wipers, each wiper has an arc b¹⁰ extending 125 around the spindle, and upon these arcs, 130

which serve as collector rings or segments, rest the ends of contact springs b^{20} carried in insulation on the right-hand side of the bridge e^3 , as shown in Fig. 1, each spring 5 having a tail b^{11} for the attachment of its circuit wire, and an extension b^{12} which receives the wiper when turned all the way around to clear it from the bank contacts and hold it in proper position for reengagement therewith, this clearing being necessary when the plate E and its attached parts are removed from the bank. To facilitate the removal and replacing of the plate in proper alinement with the base e of the 10 banks, I provide a pair of guide tongues e^2 attached to the plate e and overlying the plate E when in position. The bank as a whole is carried on four posts p best shown in Figs. 3 and 5, and each bank of contacts 15 is built up of insulating segments with the contacts radially interposed between them, the whole being held together by upper and lower segmental metal plates f secured by through-bolts or screws f' . 20

25 Coöoperating with the ratchet teeth b^6 on the wheel b^4 is the pawl b^{16} on a dog b^{14} pivoted in a yoke attached to the base plate E as shown in Figs. 1, 2 and 3. The dog has a joint in the middle, and a spring normally 30 tending to throw it up with the ratchet engaging the teeth b^6 . Coöoperating with this ratchet to form an escapement, is the armature lever b^{13} of the magnet M^1 , this lever having a chisel edge to enter the teeth, and 35 a bar b^{15} to withdraw the pawl as the edge enters, by forcing up the tail b^{14} of the dog. 40

Opposite the ratchet the dog has a toe b^{17} with which coöperates a hook on the end of the spring b^{18} carried on the end of the armature lever of the release magnet M^5 . When 45 this armature is attracted, the pawl b^{16} being up, the spring reaches up, the hook takes hold of the toe and pulls down the dog, permitting the spring b^6 to return the spindle b and all its wipers to zero position as shown in Fig. 1. 50

In order to step the wheel b^4 around, the magnet M^7 carries a pawl b^7 pivoted at b^8 and having an angle stop b^9 coming against a fixed stop b^{90} on the bridge e^3 when the magnet is deenergized as shown in Fig. 1. As the magnet M^7 is energized, its vertical lever is thrown to the left, a projection on the lower part thereof comes against the spring b^{18} to remove it from the toe b^{17} and permit the retaining pawl to rise into engagement with the teeth b^6 , the stop b^9 at the same time leaves the fixed stop b^{90} , the spring b^{80} swings the pawl b^7 around the pivot b^8 until its point engages the teeth on the ratchet wheel b^5 , each tooth on this wheel moving the arms around over five contacts m^6 at a jump, while each tooth b^6 moves the arms over one contact singly. 60

65 As the pawl b^7 pushes the wheel b^5 around, the toe b^{51} on the upper end of the armature lever comes over in the path of and serves as a stop for the teeth on a second wheel b^{90} , furnishing a positive stop for each step in the rotation. Each arm has an annular collector ring b^{19} , as stated upon which rests the spring b^{20} . When it is desired to remove the switch body from the rack, the arms are turned all the way around until they rest on the fixed contacts b^{12} , and come away with the body plate E . 70

75 Further description of the B and C switches is unnecessary in view of the statement of operation hereafter, and the fullness of the illustration. It is to be understood that I intend to claim everything I have shown, as my own invention. 80

Referring now to Figs. 6 and 7, and also Figs. 8, 9 and 10 I will point out briefly the distinctive features of the A and G switches 85 respectively shown therein. The only difference between these switches in essentials is in the number of relays they carry. Each of them has the same kind of a base plate E as that already described. Each has a similar bridge e^3 and each has its own spindle a or g and arms a' , g' etc. In Fig. 6 it will be observed the detent action of the pawls is different however, and there is but a single ratchet wheel on the spindle. The mechanical features here being identical in both switches, a single description will suffice. In Fig. 6 the magnet M^3 carries on its armature a release spring a^{18} , with a hook on the end adapted to reach up when the armature is attracted and engage a pawl carried by and pivoted on the armature lever of the magnet M^2 . When the latter magnet is energized it draws back its pawl, which is extended from a pivot beyond which it has a tail turned down like a bell crank and underlying a leaf spring on the armature lever, and the first motion releases the drop member from the spring tip a^{18} . The leaf spring immediately throws the pawl up into engagement with the teeth of the ratchet wheel. A retaining pawl a^{17} is pivoted on a bracket on the frame and when the actuating pawl rises it permits this to rise also under the influence of a spring a^{16} , and when the actuating pawl is pulled down by the hook spring a^{18} , it also pulls the retaining pawl a^{17} down with it. These two switches, A and G, have ten contacts each if ten per cent. of connective apparatus is required, 115 and twelve if twelve per cent. There is no necessity for a double movement; there is only a single actuating magnet, M^2 or M^{24} , and a release magnet M^3 or M^{23} . The arrangement of the switch base, E , and the frame carrying the bank contacts, as well as the sliding contact spring connections between the two, is the same as in the B switch. 120

125 The relays I employ are with one except 130

tion of the form shown in Fig. 4. The exception is shown at the bottom of Fig. 2, and in the middle of the bottom of Fig. 1. This is a polar relay, having a straight 5 armature resting on a knife edge on the end of its core and tilting one way or the other according to the direction of current and consequent magnetic polarity of the soft iron core and armature. Straddling the entire winding is a permanent magnet 10 secured at its neutral point to the inactive end of the core. On one arm of this magnet is secured a leaf spring having its end bent up and resting upon the raised middle portion of the armature over the knife edge, so as to hold the armature in position. Along 15 the other arm of the magnet I secure a contact spring forming one side of the circuit to be controlled, the armature forming the other.

20 The magnets M^{10} , M^5 , M^{23} , M^2 , have contacts in addition to being working magnets. In each case the contacts are secured to the frame of the magnet and are actuated by a 25 bell crank lever, one end of which is the armature.

Referring now to the circuits, first of all it will be observed that I have shown at the 30 subscriber's station what is known as Strowger apparatus, the essential parts thereof comprising the dial and receiver hook with the contacts controlled by each being arranged and operated as in the standard apparatus of this type. That is, the receiver hook is adapted when released to put the 35 transmitter and receiver across the line through the induction coil, to render the dial operative, and when depressed the hook opens said bridge and in its downward movement momentarily closes both sides of the line to ground to effect the release of the 40 switches. The dial when thus rendered operative is adapted when actuated to open the bridge of the subscriber's instrument 45 and in its retrograde movement to ground the vertical side of the line one or more times to transmit a corresponding number of current impulses thereover and upon returning to its normal position to momentarily ground the rotary side of the line to 50 despatch a single impulse of current thereover and finally, in arriving at its normal position, it closes the bridge. The series of impulses sent over the vertical side of the 55 line effects the operation of one or another of the switches and the single impulse sent over the rotary side, called the confirming impulse, cuts the lines through from one switch to the next switch, *i. e.*, it renders a 60 switch inoperative when it has performed its function and renders another switch in readiness to be operated. The sub-station circuits of the Strowger apparatus needs no 65 description for those skilled in the art and it should be understood that I can substitute

other suitable means for operating the switches. The simplest form of apparatus comprises two push buttons which may be employed for performing the functions attributed to the dial above referred to, each 70 arranged to connect one side of the line to ground when actuated.

The subscriber's instrument circuit described more specifically and illustrated in Figs. 11 and 15, comprises a transmitter T, 75 a receiver R and induction coils I, a switch hook H, ringer Q and condenser C. The receiver R is shown in a local circuit 210 terminating in one winding of the induction coil I. The transmitter circuit 80 may be traced as follows: (assuming the instrument circuit to be closed by removing the receiver) (Fig. 11) from the vertical side of the line 1 by branch 30, wire 250, springs a^{50} , a^{60} , wire 240, 85 springs a^{140} , a^{150} , line winding of induction coil I, transmitter T, wire 220, springs a^{80} , a^{90} , wire 40, rotary side of line 2. Additional spring contacts a^{10} , a^{20} and a^{101} , a^{30} , a^{40} and a^{50} , are the ones operated by the dial 90 (not shown) and a^{80} , a^{90} , a^{100} , a^{110} and a^{120} are the contacts controlled by the receiver hook 4.

The subscriber's line terminates in an A switch. In starting a call the first impulses 95 come in after the A switch has selected an idle trunk through its wipers a^2 and a^{21} , and put the line thereon, and thence to a B switch, which corresponds to the first selector switches of the Strowger systems. 100 The B switch steps around its arms in obedience to impulses, each step taking five contacts, and each five contacts representing five trunks to the next order of switches. When the desired group is reached, the 105 single impulse over the other side of the line shifts the energizing circuit, and the escape- 110 ment magnet comes into play, stepping the arms back one contact at a time until an idle trunk of the group is reached. It 115 should be observed that the return movement is produced by the ordinary retracting spring.

Having gotten down to the connector 115 through these successive steps, this being the G switch shown in Figs. 9 and 14, this only has one set of contacts, representing lines, there being no such thing as trunk groups, for if a line is busy that is the end 120 of it. As party-line service is possible with this arrangement, and is also contemplated, it is necessary to provide means for permitting the last switch to come in on the calling party's own line if he wants another party on the same line. To this end I use 125 a differential relay M^{32} for this purpose, which makes and breaks the private normal or busy line as the impulses come over one side of line, but is irresponsive to metallic 130 circuit current.

The battery connections throughout the circuits are from ground to both sides the line normally, and not until the called subscriber answers is talking current cut back to the calling subscriber. By this means I am also enabled to regulate the registering as shown in Fig. 12, particularly, wherein the polarized relay, M^{33} , shown also in Figs. 1 and 2, controls the continuity of the meter trunk 10 which may run through every switch circuit from the subscriber's instrument, in Fig. 11, where the meter is shown, to the G switch in Fig. 14, terminating finally in the wiper g' which comes upon a contact which may be a solid bank, this being connected to an interrupter, so that when the desired line is selected and the wanted subscriber has answered, current will flow back through the relay M^{33} , throwing over the same, closing the meter 20 trunk, and starting the register of Fig. 11, which is associated with the calling subscriber's A switch, and continuing to run the same and to register thereon during the continuance of a connection. The feeding back 25 of interrupted current clean through the line of switches enables me to regulate the registration, that is the speed of registering, according to the character of the line called. Interrupters of different frequencies are connected to the interrupter contacts associated 30 with different classes of lines, whereby the subscriber is charged according to the class of line he calls, and it may be he is not charged at all, if the wanted party is a dead-head.

The balance of the circuits will be better understood from a statement of operation, tracing one call in its progress through all the switches.

40 The operation of my system is as follows: Referring now to Fig. 11, the subscriber desiring to make a call removes his receiver from the hook, closing the circuit of the relay M' by the following path: 45 wire 1, normally closed contacts of the relay M , one winding of the differential relay M^{32} , 12, wiper a^2 , 27 to ground, battery B, 14, winding of the relay M' , 15, 16, wiper a^{21} , 13, other winding of M^{32} normally closed contacts of the relay M , wire 2, through the subscriber's station to line wire 1. The relay M' becoming energized attracts its armature, closing and opening the various circuits. The circuit of the magnet M^2 is completed by 50 the following path: ground, wiper a^3 , 22, contacts 23 and 25, wires 20 and 9, normally closed contacts of the magnet M^2 , wire 10, magnet M^2 , wire 11, battery B to ground. The energizing of the magnet M^2 causes it to operate or vibrate, turning the spindle a to which the wipers a' , a^2 , a^{21} , a^3 and a^4 are rigidly fastened and so causing them to move over the various contacts. It will be seen that the magnet M^2 will continue to vibrate its armature and turn the spindle by

a ratchet arrangement so long as the circuit of the relay M' is closed and wiper a^3 is connected to ground. After the relay M' is energized, it is kept locked in that position by the following path: ground, wiper a^3 , 22, contacts 23, 25, 19, 18, 17, 15, M' , 14 and battery B to ground. If after making one step the wiper a^3 moves to contact m^2 (Fig. 12) and fails to get ground, the relay M' will become deenergized, open the circuit of the magnet M^2 , and thereby stop the rotation of the spindle a . If, on the other hand, the contact m^2 should be busy or grounded, the relay M' would still continue to hold up, closing the circuit of the magnet M^2 and causing the spindle to make another step. After the spindle has made one step, the circuit of the relay M is closed by the following path: battery B, 11, relay M , 70, contact m^3 (Fig. 12), wiper a^4 , wires 9, and 20, contacts 25 85 and 23, wire 22, wiper a^3 , to busy trunk m^2 , to ground. The relay M , becoming energized, attracts its armature disconnecting the wires 1 and 2 from 12 and 13 respectively. The relays M and M' will continue energized 90 and the magnet M^2 continue to vibrate, turning the shaft or spindle until the wiper a^3 fails to find a grounded or busy contact. When an idle contact is found, that is to say one free from ground, the relays M and 95 M' become deenergized, disconnecting the magnet M^2 , causing the spindle to come to rest with its various wipers resting on contacts leading to an idle first selector or B switch. The instant this happens, the wires 100 1 and 2 are again connected to 12 and 13 respectively. The contact m^2 on which the switch is arrested is now grounded or made busy by the following path: m^2 , a^3 , 22, contacts 23 and 24 to ground. This ground is 105 placed on the contact m^2 so as to prevent another incoming call to come in on the same first selector switch. It will also be noticed that when the switch has been operated the wiper a^{100} rests on the grounded contact m^{300} , thus 110 rendering it busy for outgoing calls, that is to say, calls from the G or connector switch, and that it normally rests on the contact m^{301} connected to wire 70 to actuate relay M when this is the called line picked up by a connector switch.

The calling subscriber is now connected to an idle B or first selector switch. Referring now to Fig. 12, the circuit of the relay M^4 is closed by the following path: ground, contacts 24 and 23 of the relay M' , 22, a^3 , m^2 , 34, b^3 , 41, M^4 , 40, 54, 52, 51, battery B to ground. The relay M^4 becoming energized, attracts its armature disconnecting the trunk wires 29 and 28 respectively from the wires 31 and 120 30. The trunk wire 29 is connected to the relay M^8 by the following path: contacts 71 and 72, 73, M^8 , 51, to main battery B. The trunk wire 28 is now connected to one winding of the relay M^9 by the following path: 125 130

6 contacts 74 and 75, 76, M^9 , 50 to main battery B.

The subscriber by sending in grounded impulses on No. 1 side of the line, operates the relay M^8 by the following path: 1, 12, a^2 , 29, contacts 71 and 72 of the magnet M^4 , 73, M^8 , 51, main battery B to ground. The operating of the relay M^8 closes the circuit of the magnet M^7 by the following path: 10 battery B, 51, 52, M^7 , 53, contacts 59 and 60 of the relay M^8 , 61, contacts 62 and 63 of the magnet M^8 , 65 to ground. The magnet M^7 by a ratchet arrangement causes the shaft b to which the wipers b' , b^2 and b^3 are attached, to step around a number of times corresponding to the impulses sent in over No. 1 side of the line. The magnet M^7 at each impulse causes the wipers to step over five contacts of m^7 . At the first movement 15 of the spindle, the relay M^4 , which was formerly held up by the wiper b^3 resting on the contact to which the wire 34 is connected, is now held up from the wiper b^3 which rests on the broad terminal of wire 48 by the following path: 48, contacts 47 and 46 of the relay M^4 , 45, 43, M^5 , 44, contacts 77 and 78 of the magnet M^9 , 79 to ground. Therefore, the relay M^4 will continue to hold up while the spindle is being rotated by the magnet 20 M^7 .

After the first set of impulses have been sent over No. 1 side of the line, a momentary ground is placed on No. 2 side of the line which closes the circuit of the relay M^9 by the following path: 2, 13, a^2 , m^4 , 28, contacts 74 and 75 of the relay M^4 , 76, M^9 , 50, to main battery B and ground. The operation of the relay M^9 opens the contacts 77 and 78 and if at that time the wiper b^3 was resting 25 on a contact m^6 that was not grounded, the relay M^4 would become deenergized and connect the trunk wires 29 and 28 to the wires 31 and 30 respectively. At the same time it would disconnect the relays M^8 and M^9 that 30 it had previously connected. If, however, the wiper b^3 was resting on a grounded contact, the relay M^9 would hold up through one of its windings by the following path: ground, m^6 , b^3 , 42, 43, M^5 , 44, contacts 77 35 and 80 of the relay M^9 , 81, 82, other winding of M^9 , 50, battery B to ground. The circuit of the magnet M^{10} is also closed by the following path: ground, m^6 , b^3 , 42, 43, M^5 , 44, contacts 77, 80, 81, 83, contacts 84, 85, and 86, M^{10} , 87, 50, main battery B to 40 ground. The magnet M^{10} having the vibrating contacts 84 and 85, will commence to operate causing the spindle to step back step by step. In this manner we continue 45 to travel backward so long as the wiper b^3 resting on the contact m^6 finds a ground. As soon as the wiper b^3 rests on an idle contact or one free from ground, the relays M^4 and M^9 become deenergized opening the circuit 50 of the magnet M^{10} and the wipers now come

to rest on contacts leading to an idle C or second selector switch. It will be noticed that all the relays of the B switch are now in their normal position and the contact m^6 is grounded or made busy by the following path: b^3 , 42, 43, M^5 , 44, contacts 77 and 78, 79 to ground.

Referring now to Fig. 13, ground being connected to m^6 closes the circuit of the relay M^{12} by the following path: 49, 88, c^2 , 75 89, M^{12} , 90, main battery B to ground. The relay M^{12} becoming energized opens its normally closed contacts disconnecting the wires 91 and 92 respectively from the wires 94, and 93 and closes its normally open contacts, connecting the wires 91 and 92 respectively to the relays M^{14} and M^{15} .

The subscriber now being connected to a second selector or C switch sends in the second set of impulses over No. 1 side of the line operating the relay M^{14} which in turn closes the circuit of the magnet M^{17} causing it to turn the spindle c with its wipers over five contacts. The relay M^{12} is held up after the spindle begins to rotate in the same manner as the relay M^4 in the B switch as already described. The operation of this switch is identical with that of the B switch and will not be gone into in detail.

After the subscriber has sent in his second set of impulses over No. 1 side of the line, a momentary impulse is sent in over No. 2 side operating the relay M^{15} which in turn closes the circuit of the magnet M^{16} . The magnet M^{16} causes the spindle c to step 100 backward over a single contact at a time testing for an idle trunk. When such a contact is found, the relays M^{12} and M^{15} become deenergized opening the circuit of the magnet M^{16} , causing the spindle to come to rest with its wipers resting on contacts leading to an idle connector or G switch. The contact on which the wiper c^3 rests is grounded or made busy by the following path: wire c^1 , magnet M^{18} , c^1 normally 110 closed contacts c^2 and c^3 of the magnet M^{16} to ground. The calling subscriber is now connected to an idle connector or G switch containing the multiple terminals of the desired line.

Referring now to Fig. 14, ground being connected to the contact m^9 , the circuit of the relay M^{19} is closed as follows: m^9 , 95, g^3 , 96, M^{19} , 97, main battery B to ground. The relay M^{19} becoming energized attracts 120 its armature, disconnecting the wire 98 from 99 and wire 100 from 101. The relay M^{21} is connected to wire 98 by the following path: M^{21} , 102, contacts 103 and 104 of the relay M^{25} , 105, to main battery B. The relay M^{22} is connected to the wire 100 by the following path: M^{22} , 106, contacts 107 and 108 of the magnet M^{25} , 109, contacts 110 and 111 of the relay M^{26} , 112, 105 to battery B.

The subscriber by sending in the third set 130

of impulses over No. 1 side of the line, now 5 operates the relay M^{21} which in turn closes the circuit of the magnet M^{24} causing the shaft g to carry the wipers g' , g^2 , g^{30} , g^{21} and g^3 over the various contacts. The wipers are moved forward one step at a time by 10 the magnet M^{24} . The relay M^{19} , which was formerly kept energized through the wiper g^{30} resting on a grounded contact, is now 15 kept energized by the following path: battery B, 97, M^{19} , 113, 114, contacts 115 and 116, 117, contacts 118 and 119 of the relay M^{22} , 120 to ground. Therefore, so long as 20 the relay M^{22} remains normal, the relay M^{19} will be held or locked up and the shaft can be stepped around as far as necessary.

After the subscriber has sent in the third 25 set of impulses over No. 1 side of the line, a momentary impulse is sent in over No. 2 side of the line operating the relay M^{22} which will in turn open the circuit of the relay M^{19} , allowing it to assume its normal position cutting the lines through and leaving all the relays in their normal positions.

25 The calling subscriber is now connected to the contacts leading to the desired line. Suppose this line was busy. The contact m^{11} (Fig. 15) on which the wiper g^3 rests would be grounded or busy and the circuit 30 of the relay M^{19} would remain closed even though the magnet M^{22} is operated by the following path: ground, g^3 , 121, 117, contacts 116 and 115, 114, 113, M^{19} , 97 to battery B. It is evident that the relay M^{19} , 35 being kept energized, keeps the wires 98 and 100 respectively disconnected from the wires 99 and 101, thus preventing the calling subscriber listening in on a busy line.

Taking it for granted that the line called 40 for is not busy, the relays M^{19} and M^{22} become deenergized, the lines connected through and the contact m^{11} on which the wiper g^3 rests, will be grounded by the following path: 121, 117, contacts 118, 119, 120 45 to ground.

Referring now to Fig. 15, the contact m^{11} being grounded closes the circuit of the relay M^{28} by the following path: 122, a^{401} , 123, M^{28} , 124 to battery B and ground. The relay M^{28} operating, clears the called subscriber's individual line from any connection with its individual switch A^0 . The calling subscriber now being connected straight through to the called subscriber, it 55 only remains necessary to supply generator current to the called line which is done automatically by means of the grounded interrupter Fig. 15 and the relay M^{26} , Fig. 14. The circuit of the magnet M^{26} is closed periodically by the following path: ground, 60 interrupting machine Fig. 15, m^{18} , g' , M^{26} , normally closed contacts of the relay M^{29} , normally closed contacts of the relay M^{12} , 97, battery B and ground. The relay M^{26} operated in this manner opens its contacts,

disconnecting the calling subscriber and connecting ringing current out to the called subscriber's line, ringing the telephone intermittently until he answers or until the calling party hangs up. The relay M^{27} is 70 connected from main battery to one side of the trunk and the relay M^{25} is connected from ground to the other side of the trunk. So, therefore, the called subscriber upon taking down his telephone, energizes both the 75 relays M^{25} and M^{27} . It will be noticed that the relays M^{21} and M^{22} have their circuits open when the relay M^{25} operates. It will also be noticed that the relays M^{18} and M^{20} have their circuits normally open but are 80 closed as soon as the magnet M^{27} operates. Therefore, the called party in removing his telephone and operating M^{25} and M^{27} cuts off the relays M^{21} and M^{22} and cuts on the relays M^{18} and M^{20} , and in this manner has 85 supplied talking current back to the calling subscriber.

If, at the end of the conversation, the called subscriber hangs up first, it causes 90 both sides of the line to be grounded and the circuits of the line side to be opened and those of the mate side to be closed. By the line side I mean No. 1 side of the line where the operating impulses are sent in, and by the mate side No. 2 side of the line where 95 the momentary or switching impulses are sent in. By this, ground being placed on both sides at once, it will be seen that the relay M^{25} becomes deenergized by being shunted by the ground at the subscriber's 100 station, and M^{27} remains energized closing the release circuit of the magnet M^{23} which is in series with M^{13} . The closing of the two wires together at the called subscriber's station puts ground on wiper g^{21} , completing 105 the following circuit: g^{21} , wires 99, 98, relay M^{25} , to ground robbing M^{25} of current while M^{27} remains energized by current in the following circuit: Wiper g^2 , wires 101, 100, relay M^{27} , main battery B. The momentary 110 energizing of M^{27} closes the circuit of release magnet M^{23} , the latter being in series with the release relay M^{13} causes it to be energized which in turn energizes M^{11} in series with M^5 . The latter then energizes M^6 115 and M^3 . In this way all the switches will be released successively in reverse direction to the order in which they were operated to establish the connection. The releasing of the connector switch has just been described. This is followed by the release of the second 120 selector, the release relay M^{13} thereof being energized over the following circuit: battery B, wire 105, contacts o , o' , of M^{27} , wire o^2 , contacts o^3 , o^4 of M^{25} , wires o^5 , o^6 , o^7 , release magnet M^{23} , wires o^8 , o^9 , contact m^9 , (Fig. 13), wiper o^{30} , wire o^{10} , relay M^{13} , wire o^{11} , contact springs o^{12} , o^{13} , to ground. Likewise M^{11} is energized by action of M^{13} 125 to release M^5 of first selector switch, M^{14} re- 130

ceiving current over the following path: battery B, wires p , p' , p^2 , magnet M^{11} , wire p^3 , contact springs p^4 , p^5 of M^{13} , wires p^6 , 49, contact m^6 , (Fig. 12) wiper b^{30} , wires 5 42 and 43, relay M^5 , wire 44, contact springs 77, 78, wire 79 to ground. Similarly M^3 closes the circuit of release magnet M^6 of the first selector and M^3 of the line switch of calling subscriber, as will be seen by 10 tracing the following circuits: ground, wire 79, contact springs 37, 38 of relay M^5 , wires 36, 33 and 35, release magnet M^6 , wires 54, 52, 51, battery B, ground. M^3 receives current over the following circuit: ground, 15 wire 79, contacts 37, 38, wire 33, terminal 33^m, wiper a^{30} , wire 21, release magnet M^3 , wire 14, battery B, ground. Therefore, when the relay M^{21} is disconnected, the entire set of switches is released and returned to their 20 normal position.

If the calling party hangs up before the called party he momentarily grounds both sides of the line, which breaks the currents of the line side including M^{18} and closes 25 those of the mate side holding up M^{20} . This combination closes the release circuits and causes the same operation just described over the last described circuits. Now supposing that the called party did not answer 30 or was busy, then both sides of the line would be closed momentarily to ground at the calling subscriber's station, causing the relays M^{21} and M^{22} to pull up at the same time, which closes the release circuit and 35 thereby releases the switches in the same manner. The circuit of relays M^{21} and M^{22} may be traced as follows: ground at subscriber's station, line and mate conductors 1 and 2 through the several switches to wire 40 98 (Fig. 14) relay M^{21} , wires 102, 105, to battery B; wire 100, relay M^{22} , wire 106, contact 107, springs 110, 111, wires 112, 105 to battery B.

Having thus described my invention, what 45 I claim and desire to secure by Letters Patent is:

1. In an automatic telephone system, the combination with the subscriber's instrument circuits having means for despatching 50 impulses of current thereover and trunking and connector switches for interconnecting them, the trunking switches comprising terminals arranged in groups and the connector switches being tied to the separate terminals in said groups, of wipers coöperating 55 with said terminals, electromagnetic operating mechanism for advancing said wipers adapted to respond to impulses of current in the instrument circuits to move the wipers 60 into engagement with one terminal of a given group, and arresting them in such position and other operating devices automatically actuated when the switch connected to the selected terminal is busy to move said 65 wipers within the group of terminals into

engagement with a terminal connected to an idle switch.

2. In an automatic telephone system, the combination with the subscriber's instrument circuits having means for despatching 70 impulses of current thereover and trunking and connector switches for interconnecting them, the trunking switches comprising terminals arranged in groups and the connector switches being tied to the separate terminals 75 in said groups, of wipers coöperating with said terminals, electromagnetic operating mechanism for advancing said wipers adapted to respond to impulses of current in the instrument circuits to move the wipers 80 into engagement with the last terminal of a given group and other devices for causing a retrograde movement of the wipers, which are actuated when the switch of said last group terminal is busy.

3. In an automatic telephone system, the combination with subscriber's instrument circuits having means for despatching impulses of current thereover and trunking and connector switches for interconnecting them, the trunking switches comprising terminals arranged in groups and the connector switches being tied to the separate terminals in said groups, of wipers coöperating 90 with said terminals, mechanism for operating the wipers into engagement with a terminal of a given group in response to current impulses in the instrument circuits, and other mechanism controlling the subsequent movement of the wipers and adapted to cause them to engage each terminal in the selected group of terminals, said mechanism being normally inoperative and adapted to be actuated whenever the wipers engage a 95 terminal connected to a busy switch.

4. In an automatic telephone system, the combination with subscriber's instrument circuits having means for despatching impulses of current thereover and trunking and connector switches for interconnecting them, the trunking switches comprising terminals arranged in groups and the connector switches being tied to the separate terminals in said groups, of wipers coöperating 110 with said terminals, mechanism for operating the wipers progressively, each movement advancing the wipers over complete groups of terminals, and into engagement with the last terminal of each group and other mechanism for operating the wipers retrogressively into engagement with the other terminals of any group.

5. In an automatic telephone system, the combination with subscriber's instrument circuits having means for despatching impulses of current thereover and trunking and connector switches for interconnecting them, the trunking switches comprising terminals arranged in groups and the connector switches being tied to the separate terminals in said 125 130

groups, of wipers coöperating with said terminals, mechanism for operating the wipers progressively in response to current impulses in the instrument circuits, each advance movement of the wipers carrying them over a complete group of terminals, and into engagement with the last terminal of each group and other mechanism for operating the wipers retrogressively into engagement with the other terminals of any group, said last mentioned mechanism being normally inoperative but adapted to be actuated to cause retrogression of the wipers each time they engage terminals of busy switches.

6. In an automatic telephone system, the combination with a plurality of normally open instrument circuits, a line switch for each circuit having a bank of terminals and 20 wipers coöperating therewith and forming part of the instrument circuits, a plurality of connector switches having terminals for the instrument circuits, and wipers coöperating therewith and trunk switches comprising terminals and cooperating wipers, trunk circuits connecting similar terminals of the line switches in multiple to the wipers of the trunk switches, trunk circuits connecting similar terminals of the trunk switches 25 to the wipers of the connector switches, said terminals being arranged in groups, of electromagnetic mechanism for operating the wipers of each line switch which is adapted to be actuated when its instrument circuit is 30 closed to select a trunk circuit leading to an idle trunk switch, electromagnetic devices under the control of the instrument circuits for causing the trunk switch wipers to move progressively over complete groups of terminals, other devices for operating them retrogressively to engage terminals of an idle connector switch in the selected group, and mechanism also under the control of the 35 instrument circuits for operating the wipers 40 of the connector switches.

7. In a telephone exchange system, a movable switch terminal, stationary contacts arranged in groups traversed by said terminal, means for moving said terminal in one direction to select the desired group, and means for moving said terminal in a reverse direction to select an individual contact in said group.

8. In a telephone exchange system, a movable switch member, stationary contacts arranged in groups traversed by said terminal, means for moving said terminal in one direction to select and establish connection with the last terminal of a desired group if said terminal is idle, and means for moving said terminal in the reverse direction when the said last terminal is busy and to continue such retrograde movement until an idle terminal is selected.

9. In a telephone exchange system, the

combination with a selector apparatus having a movable contact member, contact terminals with which said member coöperates, means for imparting to said contact member a selective movement past said contact terminals in one direction, and means for causing a selective movement by said contact member in the opposite direction.

10. In a telephone exchange system, the combination with a selector apparatus having a movable contact member and groups of contact terminals with which said member coöperates, means for moving said contact member past said contact terminals in one direction to select a group thereof, and means for controlling the movement of said contact member in the opposite direction to effect the selection of a contact terminal in the selected group.

11. In a telephone exchange system the combination with a connecting circuit, of a selector comprising a movable brush carrier and banks of line terminals arranged in groups, driving means for moving said brush carrier in one direction, a sender device associated with said connecting circuit for controlling said driving means to move said brush carrier to select a group of line terminals, electromagnetically controlled means for retaining said brush carrier in such selecting position, and means for operating said retaining means to intermittently release said brush carrier and allow it to be moved step-by-step until an idle line has 95 been found.

12. In a telephone exchange system, the combination with a connecting circuit, of a selector switch comprising a movable brush carrier and banks of line terminals arranged in groups, electromagnetically controlled means for moving said carrier, a sender associated with said connecting circuit for controlling said means to move said brush carrier in one direction to select a group of terminals and electromagnetically controlled means intermittently operated to cause said carrier to move in the reverse direction to select a desired line in said group.

13. In a telephone exchange system, the combination with a connecting circuit, of a selector switch comprising a movable brush carrier and banks of line terminals arranged in groups, electromagnetically controlled means for moving said carrier, a sender associated with said connecting circuit for controlling said means to move said brush carrier in one direction to select a group of terminals, and electromagnetically controlled means intermittently operated to cause said carrier to move in a reverse direction to select an idle line in said group.

14. In a telephone exchange system, the combination with a connecting circuit, of a selector switch comprising a movable brush carrier and banks of line terminals arranged

in groups, driving means for said carrier, a sending device associated with said connecting circuit arranged to control said driving means to move said carrier to select a group of line terminals, electromagnetically controlled means for retaining said carrier in its displaced position, and means for operating said retaining means to release said carrier step-by-step until an idle line has been found.

15. In a trunk line selector, a selecting magnet and circuit, trunk line terminals, a movable terminal connected with calling line, selecting armature, means that move

the movable terminal in one plane, and in one direction to engage in succession its series of trunk line terminals, means whereby the selecting armature releases said means, and means to restore the movable terminal in the same plane but in an opposite direction until it engages the first unused trunk line terminal.

In testimony whereof I affix my signature in presence of two witnesses.
